ELECTRON TUBE CIRCUIT

Kurt Schlesinger, West Lafayette, Ind., assignor
to Radio Corporation of America, a corporation
of Delaware

Application May 11, 1943, Serial No. 486,521

34 Claims. (Cl. 177—352)

1

The present invention is directed to electron tube apparatus. It is particularly concerned with circuit arrangements adapted primarily for amplification, although many other uses, which known types of amplifiers cannot fulfill, will be set forth by these specifications.

Such apparatus may be generally considered as involving a type of circuit incorporating a plurality of grid controlled rectifier tubes which may be arranged in cascade and all of the tubes are condenser loaded. All of rectifier tubes of the cascade are so controlled as to operate in sequence. The circuit is so arranged that each rectifier has its grid or control electrode connected to the preceding condenser and the charge in the first condenser is repeated in all following condenser stages.

In the system, the operational sequence, in its broadest sense, starts with the first tube and carries through to the last tube, with the total sequence time being substantially equally divided between the several tubes. The tubes may then be rendered operative in sequence by an appropriate distributor mechanism or, more conveniently, as will hereinafter be set forth, by an appropriate source of alternating current supplying operating voltages to the tubes to permit operation on the positive half cycles. With such operation, an indication at the last tube of the sequence will be the result of some signal control effective on the first tube of the sequence a number of cycles of operation prior to the observance which is equal to the total number of tubes in the sequence.

With this arrangement, the system may be considered as incorporating a plurality of tubes arranged in at least two "groups" by virtue of alternate connection of the anodes and cathodes of successive tubes of the cascade to the source of alternating current. In this way, the tubes of alternate "groups" operate simultaneously in that all tubes whose anodes are connected instantaneously to receive the positive half cycle of the alternating current wave will be operative, while those tubes whose cathodes are connected to receive simultaneously this same half of the alternating current wave will be inoperative. During the following half cycle of the alternating current, the operation will be reversed, and so on. In this way, the various tubes may be considered as being arranged in at least two "groups" with the tubes of alternate "groups" operating simultaneously. In connection with the mode of operation hereinabove mentioned, it should be pointed out that the tubes in the different

2

"groups" operate simultaneously with regard to the energizing voltage, but that the signal wave passes through the tubes sequentially. The division hereinabove made with regard to the two groups of tubes comes about by reason of the assumed A. C. operation. The operation essentially is sequential signal transfer from one stage to the next succeeding stage, and so on. Within the meaning of the above explanation, the broad classification of "groups" will be understood in its generic sense and each "group" may thus include one or a plurality of tubes.

It accordingly is apparent that the circuit herein to be set forth operates with delayed outputs, in contrast to the practically simultaneous input and output of the usually known amplifiers. The present circuit operates, as will be seen, with linearly averaged effects of input control energy so that it may be used as a D. C. amplifier as well as an A. C. voltmeter. In the latter case, it exhibits inherent selectivity and phase response which makes it readily adaptable to use as a locator or protective signalling device.

Generally speaking, the arrangement as it is set up is so constituted that the rectifying tube circuits are grid controlled but operated with the plates or anodes supplied with alternating current voltages of predetermined and suitable frequency which is, to some extent at least, dependent upon the use to which the circuit is to be put. The tubes of the sequence have the cathode elements thereof alternately connected either to the positive or to the negative terminal of the A. C. supply energy source. The tubes are all connected so that the plates or anodes connect to the supply energy source through energy storage circuits, and each plate or anode connects directly to the grid or control electrode of the next tube. Thus, all tubes subsequent to the first of the plurality are arranged so as to be controlled by an electrical charge accumulated by the preceding storage circuit which is charged under the initial control of energy flowing in the first tube. In the usual form, the storage circuits comprise primarily a condenser element which is shunted by a resistance or a correcting inductance element, which condenser is arranged to retain its charge for at least the period of the alternating current supply wave which supplies operating voltage to the tube plates or anodes.

Thus, it is an object of the present invention to provide a highly selective electronic amplifier operating in such a manner that the plates or anodes thereof are energized by an exciting alter-

nating current of any desired frequency ranging, for instance, from that of the ordinary power supply lines or mains, for instance 50 or 60 cycles, to frequencies of ultra-high value.

Among the more specific objects of my invention are those of providing an electronic amplifier arrangement which particularly adapts itself for use in the detection of field strength variations, and particularly in an alternating current field having substantially the same frequency as that of the energy supply frequency.

A further object of the invention is to provide an electronic amplifier circuit particularly adapted for the production of single side-band transmission systems.

Another object of the invention is that of providing an electronic tube circuit particularly adapted for the measurement of direct currents and direct voltages, and thus particularly useful in connection with photo-electric tube measurements, thermo-couple measurements, ionization and the like.

A further object of the invention is that of providing an electronic tube circuit particularly adapted for detecting magnetic or electrostatic field disturbances so that the tube circuit itself is capable of providing an indication of the actual location and distance of the point from which the disturbance was initiated. In addition, it is an object to develop a tube circuit which shall be capable of simultaneously indicating the source of a plurality of simultaneously occurring disturbances.

The system, in its preferred form, is not only capable of making measurements of the type hereinabove named, but is also so constituted as to be capable of reducing measurements of distance, elevation, thickness, pressure and the like to ones of capacity, inductance or resistance.

Still a further object of the invention is that of providing measuring apparatus particularly useful for making all types of alternating current measurements, such as inductance, capacity, resistance, voltage, current, phase and the like. Also, the arrangement herein to be disclosed is generally capable of providing for making pH measurements and furthermore indicating the sign of the pH.

A still further object of this invention is to provide a circuit and apparatus for use in locating the presence or position of intruders in electrostatic or magnetic fields. In such arrangement, the system is particularly adapted for locating submarines, land and sea mines, airplanes in flight, and for use as collision prevention between airplanes, as well as for indicating the path of direction of motion of airplanes, motorcars and all forms of transports on land, sea and in the air.

A further object of the invention is to provide an electron tube circuit particularly adapted for measuring altitude or elevation, for instance, the elevation or altitude of airplanes relative to ground through an indication of the capacity changes between the airplane and ground. In this connection it may be pointed out that the system is, generally speaking, somewhat more sensitive in the region reasonably near ground, although it is generally useful, irrespective of the actual height from ground.

As a further object of the invention the system is to be designed for use in connection with the protection of buildings and for protection against when an object is moved within the field of the equipment.

A still further object of the invention is that of providing apparatus for use in geodetic work, and particularly for locating water, oil or ore.

5 A further object of the invention is that of providing a system which does not alter its operational phase, and therefore, the number of stages of the amplifier is substantially immaterial, except for the degree of amplification desired and the sensitivity of response.

10 A further object of the invention is that of providing an electronic circuit arrangement which will function as a radio receiver with substantially constant band width no matter which of a plurality of carrier frequencies is received, and a further object of the invention in this connection is that of providing an audio amplifier with a substantially constant band width.

15 Other objects and advantages of the invention will immediately become apparent to those skilled in the art from a reading of the specification and the claims, taken in connection with the drawings, wherein,

Fig. 1 is a circuit diagram of a generalized form of the circuit of a two-stage amplifier;

20 Fig. 2 is a modification of the circuit of Fig. 1 provided with additional amplification stages;

Fig. 3 is a graphical analysis to indicate generally the principles upon which the system operates;

25 Figs. 4a, 4b, and 4c are a series of curves to indicate generally the phase and frequency responses of the systems of the character shown by Figs. 1 and 2, for instance, to indicate the possibilities of alternating current measurements;

Fig. 18a is a series of diagrams to indicate the response conditions of the indicating tube of Fig. 18; and,

Fig. 19 shows a modification providing a different form of bias for the first stage.

Referring now to the drawings, and first to Fig. 1 thereof, there is shown a general circuit arrangement including only two tubes which will indicate substantially the general operational principles of the invention as above outlined. In the arrangement of Fig. 1, there are provided two separate thermionic tubes 1 and 2 which may be of any general and desired type, and which have herein been illustrated schematically as tubes of the general triode type, although it is to be understood that any suitable multi-electrode tubes may be used with equal efficiency.

In the output circuit of the tube 1, there is provided a storage circuit comprising a condenser 3 and a resistance 4 which shunts the condenser. This parallel combination of resistance and capacity is connected, on the one hand, to the anode or plate 5 of the tube 1, and, on the other hand, by way of the adjustable contactor 6 to a desired tapping point on a potentiometer 7. One terminal of the potentiometer connects to the cathode 8 of the tube 1 by way of the conductor 9 which is, in turn, connected to one end of the secondary winding 10 of a transformer 11, and the other end of the potentiometer 7 connects by way of a conductor 12 to the opposite end terminal of the transformer secondary winding 10 and also to the cathode 13 of the tube 2.

The control electrode 14 of the tube 2 is connected both to the plate or anode 5 of the tube 1 and to the condenser or storage element 3, and the plate or anode 15 of the tube 2 connects to another storage circuit including the condenser 16 and resistor 21, to one terminal of which an indicating element (assumed to be the meter 65) connects. The condenser of the storage circuit has its other terminal connected to the second terminal of the transformer secondary 10 through conductor 25, as does the cathode 8 of tube 1 and the conductor 9.

Alternating current energy for energizing both of the tubes 1 and 2 is supplied to the transformer primary 19 by way of input terminals 20 upon which alternating current energy of any suitable frequency is impressed. Input signals which are to be amplified, for instance, are impressed by way of the input terminals 22 so as to be applied to the control electrode 23 of the tube 1 across the resistor 24 which connects at one end to the control electrode or grid 23 and at the other end to the cathode 8.

The system hereinabove described is believed to operate in the following manner:

Assume, for instance, that the alternating current energy applied through the transformer 11 is supplied so that the conductor 12 is positive with respect to ground (or conductor 25), and that the conductor 25, which supplies the anode voltage to the tube 2 and connects also to the cathode 8 of the tube 1, is negative relative to conductor 12. It is apparent, under such circumstances, that the tube 1 will draw current but that the tube 2 will be blocked because the cathode 13 of the tube 2 will be carried positive with respect to its plate or anode 15, but with regard to the tube 1, the anode 5 will, by virtue of the application of the positive half cycle of alternating current wave impressed by the transformer 11, be carried positive relative to its cathode 8. Therefore, under this positive half of the alternating current wave impressed by the transformer 11, the tube 1 will draw current. When tube 1 draws current, it will charge its plate condenser 3 in accordance with the emission within

the tube 1. The current flow through tube 1 is, in turn, controlled by the average grid voltage existing during the half cycle of conduction as it appears across the grid leak resistor 24 as controlled by the impressed voltages at the input terminals 22. However, during the next half cycle of the alternating current energy impressed through the transformer secondary 10, it is apparent that the opposite state will exist so that the conductor 12 will become negative relative to the conductor 25, and thus the anode or plate 15 of the tube 2 will become positive relative to cathode element 13. Accordingly, the charge impressed in the condenser 3 by virtue of the previous half cycle period of conductivity of the tube 1 will be measured by the tube 2 which now becomes conductive. It should be borne in mind that the bias on grid 14 is constant (or approximately thereso) due to the fact that the time constant of circuit 3, 4 is long. This then provides a current flow into the storage condenser 16 which will be a measure of the charge of the preceding condenser 3. It will be appreciated that if a direct current is impressed at the terminal 22 it will appear amplified in the average plate current of tube 2, provided the time constant of the circuit comprising the condenser 3 and the resistor 4 is longer than, or at least equal to, the period of the alternating current wave supplied at the terminal points 20.

Normally, in the circuit hereinabove disclosed, there is a direct current voltage drop across the resistor 4 which is due to the mean value of the plate current flowing from the tube 1. This voltage drop normally would block the tube 2, completely, unless it is compensated for by a suitable bias. It has been found, however, and is a feature of this invention, that the unblocking of the tube 2 may be effected by an alternating current voltage as well as by the direct current voltage, provided that the alternating current voltage is in the right phase with respect to the power supply of the second tube. Such conditions may be fulfilled by the use of the potentiometer 7 which is set to such a value that the plate current to the tube 2 assumes its mean value in accordance with the current flowing in the tube 1. It is important to note that the A. C. voltage drop between the tapping point 6 on potentiometer 7 and conductor 12 has the same effect as would have an equivalent D. C. bias or battery between these points.

The two currents then change in the opposite sense, if the system is at balance under the control of an input signal voltage to be measured. Accordingly, it may be seen that the system described is capable not only of amplifying small value direct currents or direct current voltages impressed across the resistor 24, but also alternating currents or voltages, provided the frequency thereof is approximately that of the alternating current energy source connected at 20 and the beat note (if resulting) is at least in the response range of the storage circuit, as will later be set forth in further detail.

Referring now to the arrangement of Fig. 2, it will be understood that like parts are referred to by like numerals in this figure, as in all others. The arrangement of the circuit in Fig. 2 is essentially similar to that hereinabove described in connection with Fig. 1, except that the arrangement is used as a multi-stage amplifying device. In the arrangement of Fig. 1, each stage, such as the tube 2, has its own voltage divider 7 which adjusts its operational bias to optimum condi-

tions. If more stages are added with the circuit of Fig. 1, each subsequent stage must be separately biased. Since subsequent stages depend upon the preceding stages, difficulties are present which increase with the number of stages. To overcome such difficulties, a self-biasing system is shown by Fig. 2. With the arrangement of Fig. 2, provision is made whereby appropriate bias is applied only to the first tube 1 of the series and the remaining tubes 2, 39, 40 and so on function as self-biasing devices.

From the foregoing, it will be appreciated that any changes of control signal energy applied to the input terminals will be first observed in the output indicator circuit 16, 21 and at the output terminals 17 and 18 (or the indicating device 65) at a time $n/2$ cycles of the supply A. C. later, where n represents the number of stages in the system. This permits a ready control of transit time of signals through the system by a variation of the frequency of the A. C. power supplied at power input terminals 20, and thus serves to adapt the system to certain of the uses above stated and explained further in what is to follow.

Considering now Fig. 2, it will be seen that no individual bias control has been provided for any of the stages, except for the first one, which is denoted by resistor 31 and potentiometer 30. Even despite the absence of individual controls, all stages may be made to draw equal amounts of average emission, i. e., all stages may be made to operate under equal conditions if only the first stage is adjusted separately and critically, for example, by the potentiometer 30.

To show this, it may be assumed that the first stage 1 is permitted to draw a particularly strong emission, under the influence of a strong positive control signal at any instant. Then, there will be an unusually strong negative residual charge across its plate condenser 3 which, during the next half cycle, now acts as grid bias for the next valve in the connection shown. The second tube 2 of the system may thereby be completely cut off during its supposedly conducting half-cycle, which follows. This, in turn, results in zero charge across condenser 33 and therefore is zero bias for the next stage 39. This third stage, therefore, produces a strong and blocking bias for the fourth stage, and so forth.

It will be apparent, therefore, that the average emission and charges of the first, third and fifth stages, and so forth, are strong, but of the second, fourth and sixth are zero.

The opposite distribution would hold, if the first stage had been less conductive or even blocked off, by a strong negative signal, at the time of its supposedly conductive half-cycle.

It is, therefore, possible to bring the entire system into a condition of balance, where all stages draw equal average emissions and operate under equal conditions, simply by setting a critical medium average emission in the first tube 1. With any given input signal, this can be done by applying an appropriate bias to the cathode 8 of first tube 1. As outlined before, this may be either a D. C. bias, an equivalent cophaseal A. C. bias, or a rectified A. C. bias, as disclosed later herein in connection with Fig. 19. The latter is shown in Fig. 2, as derived from the common A. C. supply by an ohmic voltage divider consisting of resistor 31 and potentiometer 30. With the help of this system, the entire system may be brought into balanced condition and the output indicator 65 to "center-scale."

This operation will be more particularly un-

derstood by reference later to be made to the diagram of Fig. 3. At present, it will be seen that the tube 1 has appropriate A. C. bias applied by way of the resistor 31 and potentiometer 30 which has its center tap connected by way of the conductor 32 to the cathode element 8 of the first tube 1. The bias arrangement provided by the potentiometer and its variable tap 6 (see Fig. 1, for example) between each stage is avoided, and only the first tube of the series is maintained at a manually adjusted bias level in Fig. 2. If, under such circumstances, input signals are applied, as in Fig. 1, to the input terminals 22, they now affect the control grid 23 of the tube 1 and function to control the current flowing therethrough, and thus determine the charging of the condenser 3, as explained in connection with Fig. 1. In the arrangement of Fig. 2, however, it will be seen that the tube 2, representing the second tube in the series, now functions to draw current at times when the tube 1 is blocked. In this way, the condenser 33 of the condenser and resistance network 33 and 34 is then charged under the control of the storage voltage of the first storage circuit 3, 4, and consequently, the third tube 39 in the series will be conductive at the same time as the first tube. The bias on tube 39 is constant and determined by the slow discharge of the storage condenser 33 through its shunt resistor 34, which discharge is negligible (as was discharge from condenser 3) during a half cycle of the A. C. at the terminals 20. At times when tube 2 ceases to draw plate current, it is apparent that the tube 39, that is, the tube illustrated as the third in sequence, will draw plate current and tend to charge the condenser element 43 of the condenser and resistance combination 43 and 44. It then happens that the operation is such that the charge is next transferred at the fourth half-cycle by tube 40 into its storage circuit and the rest of the operation naturally follows accordingly.

Alternating current voltages are applied as the plate voltages for all of the tubes of the series, with the alternating current energy connected at the power input terminal 20 and then through the windings 19 and 10 of the input transformer 11, so that the tubes 1, 39 and 41, respectively, have their plate circuits energized by alternating current energy flowing in the conductor 12 and controlled by the stabilizer resistance 46, while the tubes 2, 40 and 42, for instance, have alternating current potentials applied thereto by way of the conductor 25.

If now, particular reference is made to Fig. 3, it will be seen that there is plotted a schematic representation of the effective grid bias on the first tube 1 as the abscissae with resulting plate current indicated as the ordinate. If now, it be assumed that the tube 1 cuts off at some value of its grid bias indicated by point *a*, then various plate currents will flow through the tube 1 for all values of grid bias between that indicated at *a* and zero bias, which may conveniently be represented by the line drawn between point *a* and point *b* on the curve (and marked "Tube 1") which is the rectifier characteristic of the stage with A. C. power supply. Point *b* in this instance will represent some current which will flow through the tube 1 for zero bias, which conventionally may be represented as current *I_o*.

It was above explained that at times when no average current flowed through the tube 1, the storage voltages appearing in the condenser 3 are zero and, consequently, under such circum-

stances, the tube 2 draws a current I_0 which is represented by the value c . This current in tube 2 will decrease as the average current in tube 1 increases. This current in tube 2 will become zero when the average voltage drop across the first storage circuit is equal to cutoff (that is, $o-a$). The critical first stage current to bring about such a condition (cutoff voltage) is readily found from Fig. 3 by reference to the "Load line" which is drawn through the original O at an angle B where the tangent of the angle B is equal to the value of resistance 4. This "Load line" indicates the cutoff value of primary current (I_c) where it intersects the current ordinate $a-c$ at point f .

It will be appreciated that the value of bias on tube 1 necessary to provide cutoff in the second tube 2 will be that value e which is represented by the point at which the first tube has a current I_c . Thus, whenever tube 1 draws a current equal to (or greater than) I_c , tube 2 is cut off. This happens at point d and the appropriate bias for the first stage is found at point e , beneath d . Hence, the overall characteristic for two stages is represented by the line $c-e$.

Likewise, following the same analysis, it is apparent that the next point for cutoff in tube 39 (the third tube) is readily found to be at the point g , while the point at which maximum current flows through the tube 39 is found to be at point h . From what has been stated, the overall characteristic over three stages may be assumed to be represented as that line which is drawn between points g and h .

It is now apparent that all of the characteristics conventionally represented for the tubes 1, 2 and 39 pass through, or approximately through, some common point s , where all stages pass equal current after a condition of bias is established on tube 1, which can be brought about by the bias value represented by the point t , which is the bias applied to the first stage to provide this equilibrium condition.

It can be seen now that the tubes of the sequence have gradually steeper overall characteristics, with the last of a series of n tubes being the steepest, and which, for instance, might be represented by the characteristic m, x, s, v, w . It thus becomes apparent that the increase in slope in the overall characteristic, which is desired from the standpoint of amplification, is balanced against the decrease in the range of applied bias voltages, such as e, g , as compared to a value o, a of grid bias on the first tube above. However, for control bias within the range between values represented at points g and e , amplification may take place with extremely high undistorted gain due to the steepness of the overall characteristic represented conventionally by the curve m, x, s, v, w .

In the foregoing description, reference was made particularly in connection with Fig. 3 to an explanation of the operation of the circuits of Figs. 1 and 2, where the system was assumed to be controlled by a constant voltage or D. C. signal applied to the first tube of the system, that is, tube 1, to control the resultant output of the system and consequently to provide amplification of that voltage at the output terminals 17 and 18. The system, however, is capable of functioning under certain conditions equally well under the control of applied alternating current signals on the input terminals 22. To this end, Fig. 4 will explain how A. C. observations are achieved.

If reference be made now to the several curves of Fig. 4, it can be seen from curves of Fig. 4a that the alternating current supply frequency is represented by a sinusoidal voltage wave designated by the solid line E_s which is of a frequency represented by f_s . If now, a condition be assumed where the controlling signal voltage shown by the dot-dash line E_i impressed upon the input terminals 22 is of a like frequency and in phase exactly with the supply frequency E_s (as impressed upon the power terminals 20) then it can be seen that the plate current in the first stage has the form shown by curve I_p , (dash-double-dot line) in Fig. 4a. Since current does not flow through the tube 1 for half of the cycle of the supply voltage E_s appearing at the terminals 20, it is apparent that the instantaneous current flowing through the tube 1 for the negative half-cycle will be zero, as is indicated, notwithstanding the fact that the impressed voltage E_i is applied to the input terminals 22 for the full duration. The plate current I_p is not directly observed, but the output measurement is directly proportional to the charge which this current produces in the first storage condenser 3 and is thus represented by the shaded area marked "Average current." Where a cophaseal state of supply and signal voltages exists, then this shaded area, and hence the output reading, is a maximum, because the signal grid voltage E_i is positive during the conductive period.

A condition may now be assumed where the signal voltage E_i is again of the same frequency f_s as the power supply voltage but 180° out-of-phase at the terminals 22 with regard to the power supply voltage E_s supplied at power input terminals 20. These conditions are graphically represented by the curves of Fig. 4b. In this case, the instantaneous current flowing through the tube 1 of the system is represented by the dot-dash line I'_{pl} . It is of reduced magnitude relative to the current represented by I_{pl} in Fig. 4a for a cophaseal case, because the signal grid voltage E_i is now negative during the conductive period. Accordingly, the output indicator-reading, which measures the area shaded under the curve I'_{pl} (that is, the charge across storage condenser 3) is smaller than was indicated in Fig. 4a and can become zero in some extreme cases of strong negative signal input.

The foregoing is illustrative of the fact that the storage device is responsive to A. C. signal inputs, provided that they are of the same frequency as its supply. These principles thus become the basis of operation of the storage principle circuits shown and described in the remaining figures of the application.

The foregoing considerations apply to conditions where the signal and supply frequencies are equal. If the supply frequency is given, the system does not respond to any arbitrary frequencies but rather only to discrete frequencies. The circumstances for such spectral response are shown by Fig. 4c. The system responds best (greatest sensitivity) to all frequencies which are an integral multiple of the supply frequency, with the inclusion of direct current (zero frequency, $1f_s, 2f_s, 3f_s$ and so forth, where f_s represents the supply frequency). The higher the signal frequency carrier, the less will be the response, as shown by Fig. 4c. Where the signal frequency differs from the supply frequency, the response is reduced and becomes zero periodically.

Referring now further to the curves of Fig. 4c for a more complete understanding of the inven-

tion, the response of the storage amplifier for various conditions for various frequencies of signal input relative to the power supply frequency is shown. It is apparent from Fig. 4c that the amplifier is selective.

It was above shown that the system responds both to direct current signals and to alternating current signals of the same frequency as the supply. With reference to curve of Fig. 4c, conditions may be seen where the amplifier also responds to different frequency values selectively, where such frequencies extend from zero frequency or direct current to extremely high frequencies and bear an integral relationship with regard to the energizing frequencies supplied at the power terminals 20. If, for instance, the amplifier is excited by direct current applied at the terminals 22, then the response range is that indicated with a maximum at 100% on the curve and included within the shaded response area. The band width covered within the shaded area is given by the time constant chosen for the storage circuit comprising, for instance, the condenser 3 and resistor 4, or, for instance, the condenser 33 and resistor 34, and so on. If now, the impressed signal frequency which is applied to input terminals 22 happens to coincide with the supply frequency at the power terminals 20, then a response, such as that indicated at the point where the signal input frequency is equal to f_s , that is, the supply frequency, will result. Another maximum is observed where the energizing signal frequency is twice the supply frequency, although this "second-order" response will be reduced from that condition where the supply frequency and impressed signal frequency are equal. The response range or band width is the same for all conditions, but the gain is reduced at the signal frequency $2f_s$ to about 33% from the first order response, as indicated by the curve. Likewise, if the impressed signal frequency is three times the value of the supplied frequency, the response will be about 25% that which resulted with direct current being supplied as the control signal energy, as, for instance, for still higher orders.

Accordingly, it is evident from the curves of Fig. 4c that the amplifier band width is, in each instance, the same, but the sensitivity is reduced with increasing signal frequency. It is also evident that if the signal frequency is other than some integral of the supply frequency, the amplifier will not respond and the amplifier is found therefore to be selective as to the control signal input. However, the amplifier will respond to beat frequencies which fall within the shaded areas or regions of Fig. 4c. It thus becomes apparent also that since the amplifier does not respond to impressed frequency values intermediate multiples of the supply frequency the amplifier does not pick up static or noise occurring within these ranges and shows a high signal to noise ratio performance.

The general curve showing the sensitivity for various signal frequencies at given supply frequency is that shown in Fig. 4c by "dash" lines connecting the peaks of selective signal response at the various frequency values, and it can be shown that this is a hyperbola which follows the general form—

$$\frac{\sin (nf_s)}{nf_s}$$

where n is an integral number and f_s is the supply frequency fed into the system at the terminals 20 to power it.

In Fig. 5, a further modification of the arrangement of Fig. 2 has been illustrated. In this arrangement, the signalling energy is impressed, as in Fig. 2, across the input resistor 24 by way of the output energy derived from a suitable load line or cable 50, so that tube 1 has its control electrode 23 energized in the manner hereinabove explained in order to produce the mentioned charge in the condenser 3 of the time constant circuit comprising the condenser 3 and the resistor 4 connected to the plate or anode element 5 of the tube 1. The time constant circuit comprising the condenser 3 and the resistor 4 is of the order hereinabove explained and the operation is essentially like that described in connection with Fig. 2. However, in the circuit of Fig. 5, additional stabilizing resistors 52 may be included between the various stages of the system, as indicated. With the arrangement shown, two additional stages 53 and 54 have been added in order to be able to arrange the system in groups of twin tubes to use twin triodes with the heaters coordinated in pairs.

In cases where the system is energized from alternating current voltages, it is desirable to make connection from the cathode elements of the tubes to the conductors 12 and 25, as indicated, and consequently, separate heater current paths are provided for each half of the tubes by way of the connections through the coupling transformer windings 56 and 57 respectively. Also, in the arrangement of Fig. 5, provision has been made whereby various tubes may be combined within a common envelope and, to this end, for instance, tubes 1 and 39 may be combined within a single envelope, likewise tubes 2 and 40, also tubes 41 and 53, and 42 and 54. This is always possible where the total number of stages is an integral multiple of four.

Since the gain from the system is extremely high, and since extremely high gain, as would be indicated by the curves of Fig. 3, is very difficult to control, it is desirable that some degeneration be provided within the system which can be achieved by means of cathode degenerative resistors 55 indicated. Since the system herein disclosed is sensitive to alternating current excitation, it is particularly important that suitable shielding thereof be provided in all instances. To this end, the shielding member 60 forms a housing about the complete instrumentality and all cathode elements and leads, and one side of the system is grounded, for instance, by the conductor 25 connecting at point 61 which would provide the ground of the heater of the first tube 1 of the system. It is also important that the conductor 50 supplying the control voltages to the grid or control electrode 23 of the first tube 1, have suitable shielding which is conventionally indicated by shield 62. Likewise, in order to avoid any electrostatic coupling between the primary winding 19 and transformer 11 into the secondary thereof, a grounded electrostatic shield means, indicated at 63, as is well known, is provided. In this way, the amplifier is completely insulated from external and extraneous undesired controls, and stabilization against disturbing influence thereon is provided. The excitation and resultant output, as it appears at the output terminals 17 and 18, and, for instance, is conventionally represented as influencing the meter 65, is due entirely to the control signal voltages applied upon the system by way of the input conductor 50 rather than external disturbing influences.

In the arrangements of Figs. 6 to 9, further

modifications of the system have been illustrated where the storage amplifier system is used under the influence of signal input of the same frequency as its own supply. In Fig. 6, the control is by way of a phototube which is energized by the common supply transformer and activated by external light directed thereupon. In the arrangement of Fig. 6, the phototube output is always in phase with the supply voltage wave. In the arrangements of all of Figs. 6 through 9, the signal frequency coincides with the supply frequency. As to its phase, the signal frequency and supply frequency coincide in the photo-amplifier modification of Fig. 6, while the devices of Figs. 7 to 9 are inherently out-of-phase, but phase shift is measured by the act of bringing about a cophasal condition of operation and observing maximum output.

With the arrangement of Fig. 6, the overall sensitivity of the system is large and, therefore, provision has been made by way of a variable resistance element 67, replacing the input resistor 24 of the arrangements of Figs. 1 and 2, for instance, for reducing the impressed voltages which are applied to the control electrode 23 of the first tube 1 of the system under the influence of strong illumination. In the modification of Fig. 6, the complete system is housed within the electrostatic shield means 63 in which is included a window member 68 through which light from an external source is directed upon the phototube member 69 contained within the housing. The window 68, if desired, may include a lens arrangement so as to focus sharply light which is to control the photoelectric current flowing in the phototube 69, thus to vary the control potential on the control electrode 23 of the first tube 1 of the system.

In the arrangement shown, the cathode heater of the cathode of tube 1 is connected to the shield at point 64, as in the arrangement of Fig. 5. The heater elements are arranged in groups and are separately energized by two heater coils 56, 57 which are, in turn, connected to either of the two terminals of the secondary of the power transformer 11. Such connections avoid insulation troubles.

The phototube 69 is so connected that the anode element 71 thereof connects to the conductor 12 and is supplied with alternating current in the same manner as the plate or anode 5 of the tube 1, so that, at times when the plate or anode 5 of tube 1 is supplied with energy of the positive half-cycle of the alternating current source connected at the input terminals 20, the anode 71 of the phototube will also be positive, and then light entering upon the phototube 69 to influence the photoelectric cathode element 72 thereof will provide an A. C. voltage drop across the input resistor 67 to give a positive swing on the grid or control electrode 23. The input resistor 67 is variable, so that the overall sensitivity may be readily adjusted.

The time constant of all storage circuits 3, 4, etc., is made large as compared to the supply as was outlined in what is said above. Suitable A. C. bias for the first stage of the system is applied in the same manner shown in connection with the arrangement of Fig. 2.

The amplifier of this system preferably has an odd number of stages since then the output increases with illumination on the phototube 69. The A. C. bias is set on the first stage by the slider of potentiometer 30, so that the bias on

the last stage 39 is at cutoff, which permits an indicator 65 of higher sensitivity to be used.

However, if the system is somewhat non-linear for small light fluxes, the operation may be improved by providing five stages (as hereinabove indicated in other circuits) and securing the desired linearity by providing cathode degeneration in each of the stages. Under such circumstances, as disclosed by Fig. 5, the use of cathode resistors tends to straighten the characteristic. Thus, five stages, with degeneration, provide the same photosensitivity as did the three stages, but linearity is improved.

Still another application of the invention is shown in the circuit arrangement of Fig. 7, wherein special provisions have been made for use of the device for alternating current measurements. In the arrangement shown, the energy supplied at the supply input terminals 20 is now fed through a transformer 75 which has a split secondary winding consisting of the secondary turns 76 and 77, respectively, with the center tap 78 connected to a ground point 79, as indicated, which point coincides with the connection to ground of the cathodes of the first and third tubes 1 and 39 respectively of the system. Alternating current voltages are supplied to the plate electrode members of the tubes 1 and 39 by way of the conductor 12, as described, for instance, in connection with Figs. 1 and 2, and the plate of the second tube 2 is grounded through the conductor 25.

In order to provide for making alternating current measurements, a phase shifting network, comprising the series arrangement of the capacity element 80 and the variable resistor 81, is connected between the outside terminal points of the two secondary windings 76 and 77, whereby, through adjustment of one of the elements 80 and 81, varying phase shifts may be provided between point 82 and ground 79 without changing the voltage between point 82 and ground 79. At point 82 the unknown impedance 83 is connected serially to ground 79 through switch 84 with the variable grid resistor 61 which is accurately calibrated. In this way, when voltages appear at the point 82, they are applied through the unknown impedance 83 and switch 84 to the grid or control electrode 23 of the tube 1 to control the current flowing through the tube 1 in the manner hereinabove explained.

In the operation of this system, the A. C. bias is adjustable by potentiometer 30 to a value where a cutoff condition holds on tube 39 and meter 65 is at zero reading where the switch 84 is open (as shown). Now, switch 84 may be closed and the A. C. signal transferred from transformer 75 is impressed on the grid 23 of tube 1 through the phase shifting network 80, 81 and the unknown impedance 83 in an amplitude which depends upon and is proportional to the value of the grid resistance 61. With this condition, the grid resistance 61 is adjusted until an indication just appears on indicator 65. The phase control 81 is now adjusted and, in the general case, the indication on the device 65 will go through a maximum and, when the maximum is reached, the cophasal condition of grid input voltage and supply voltage is obtained. This permits observation and determination of the phase angle of the unknown impedance 83 which coincides with that produced between elements 80 and 81 and is of opposite sign to that of the elements 80 and 81. To ascertain the exact value of the unknown impedance 83, the phase condition 75 above set by element 81 is maintained and the

value of the grid resistor 67 is reduced until the indication on 65 just disappears and then the unknown impedance can be calculated from the value of resistance 67 by voltage divider formulae. In this operation, the current flow in the outer circuit 80, 81, 77 and 76 is relatively large compared to the current flow through the unknown impedance 83 to ground 79 through the resistor 67 and, further, the grid impedance 67 is a small fraction of the impedance 83, which condition is always met with a sensitive amplifier.

Figs. 8 and 9 are modifications of what is shown in general form by Fig. 7. Figs. 8 and 9 are related to a showing for measurements of technical inductances and capacitors, respectively, with losses. The general technique is like that explained in connection with Fig. 7, except that the push-pull transformer secondary 76, 77 is no longer required due to limited phase shift to be expected. In each of the arrangements of Figs. 8 and 9, the unknown phase shift may be ascertained from the phase retarding network comprising the resistor 85 and the capacitor 86. The resistor 85 is connected in the A. C. supply lead 12 and the capacitor connects to ground 91 from point 90 which constitutes the junction point of connection of the network elements 85, 86. The calibrated resistance element 87 enables the value of the inductance 88 or capacitor 93 to be ascertained. In the case of the inductance measurement, the inductance 88 is connected between the grid 23 of tube 1 and ground 91, while the capacity element 93 will be connected between the grid 23 and the phase delayed plate supply for the tube 1. With the circuits of Figs. 8 and 9, the adjustment of elements 85 and 86 of the phase shifting network generally is of a closely related nature to the phase shift adjustment of elements 80 and 81 in Fig. 7. Likewise, adjustment of resistor 87 is for substantially the same purpose as the adjustment of resistor 67 in Fig. 7.

As in some of the preceding circuits, with the systems of Figs. 8 and 9 it will be appreciated that tubes 1 and 2 may be combined in a single envelope by using tubes of the general types of the 6F8 and 6J5 for instance.

In the modification shown by Fig. 10, provision has been made to use the principle of the circuits hereinabove explained in connection with speech transmission, as contrasted with the general type of measuring instrumentality. In the arrangements particularly disclosed in the preceding figures, it was assumed that the control signal is direct voltage or a constant amplitude alternating current voltage. Under such circumstances, the time constants of the storage circuits comprising, for instance, the charging resistor 4 and the storage condenser 3 connected to receive the output from tube 1, can be made relatively long. However, in arrangements where the signal energy is such that the signal strength varies, as will be the case to be considered in the description of Fig. 10, certain modifications must be made in the system. For instance, the supply frequency which is to energize the plate or anode elements of the various tubes will have to be of a relatively high frequency value and at least twice as great, and preferably more, as the highest signal frequency which is to be supplied to vary the input for amplification. For instance, for speech amplification the frequency of the supply energy which is to energize the plates of the various tubes of the system must now be in the higher

frequency range and preferably of the order of 20 kc. or more.

Even if the supply frequency chosen is high, the system of Fig. 2, for instance, will not handle audio control signals because of the high inertia of the storage circuits. Accordingly, the storage circuits which had a relatively long time constant in the examples heretofore discussed, must now be so designed that they have an extremely short time constant, which is preferably less than (and certainly no greater than) the shortest period occurring in the signal input, meaning the period of highest frequency which is contained in the signal input to the system. If, for instance, it were assumed that the system of Fig. 10 were to be used as an amplifying arrangement for amplifying audio voltage signal input energy and a high fidelity system were to be desired, then it will be apparent that the time constant of the storage circuits of each of the tubes should be shorter than 30 micro-seconds, since the system should function properly up to sound frequencies of the order of 10 kc., and the supply frequency then should preferably be of the order of 30 kc. or higher.

For these conditions, the circuit shown by Fig. 10 is such that energy of a relatively high frequency, as above explained, is developed at the power supply 100 and fed through the transformer 101 to energize the conductors 12 and 25, as above explained. The control signal voltage which now may be audio frequencies ranging from zero to 10 kc., may now be applied to the input terminals 103 and 104 and fed through transformer 105 to be applied upon the control electrode 23 of the first amplifier tube 1.

Since the system herein disclosed may amplify audio frequency directly, or the system may function as its own demodulator, it is possible to supply the audio frequency signals as modulations upon a radio frequency carrier which is impressed at the terminals 103 and 104. Under the conditions where the audio frequencies are applied as modulations of a carrier frequency, the secondary winding 116 of the transformer 105 (which, in this case, is a radio frequency transformer and is contrasted to audio frequency transformer where the signals do not appear as modulations of a carrier) is now preferably tuned by means of the condenser 117, but it will be understood that the condenser may be omitted in the case that the signals are supplied without being modulations of a carrier frequency.

In the arrangement shown in Fig. 10, it is to be understood that any desired number of stages may be utilized, although only four stages have been shown. Under explained conditions, with fairly extremely high supply frequencies (for instance, 30 kc. as at the source 100) and very short storage inertia, the charges across the storage condenser circuit are able to follow even the fastest rate of change of the input signal and are therefore transferred through the complete system and amplified in each stage until they appear at the last storage circuit 118 with a delay

$$\frac{n}{2} \frac{1}{30000} \text{ seconds}$$

(n=number of stages and 30 kc. is the assumed supply frequency) but otherwise undistorted. It is thus evident that the delay period is a function of the supply frequency, so that it is subject to control by varying the supply frequency and thus can be made shorter by increasing the supply frequency, although no changes are made in the

storage circuits or their time constants and the quality of the reproduction suffers no change. This system, therefore, is of the type well suited to use as a reverberation control.

The output energy which appears across the last storage condenser 118 is supplied to a sound reproducing element 119 by way of the transformer coupling 120 connected across the storage condenser.

If reference is made at the moment to the curves of Fig. 12, it will be seen that the frequency response of a circuit of the type of Fig. 10 is generally indicated by the curve *a* of Fig. 12. This curve *a* shows that the frequency response plotted against the signal frequency impressed (with the assumption that the supply frequency for the tube anodes remains constant) falls off rather rapidly with increases in input signal frequency.

Accordingly, to improve the response, reference may now be had to a further modification of the circuit as shown by Fig. 11. In the circuit arrangement of Fig. 11, the same supply frequency as above from the source 100 is again fed through the transformer 101 to energize the plates of the various tubes of the system by way of the conductors 12 and 25, as already explained. Incidentally, in order to provide suitable alternating current bias on the system, provision is made for the use of the series condensers 128 and 129 serving as a capacitive voltage divider to replace the resistive voltage divider of Fig. 10. Nevertheless, previously described bias supplies may be used at this point.

With the bias system shown, provision is made for connecting a suitable high frequency choke 130 between the cathode element 8 of tube 1 and the conductor 25 to avoid the detrimental effect of the cathode to ground distributed capacity, represented at 122 in Fig. 10.

In order that the high frequency response of Fig. 11 shall be improved over that of Fig. 10, the storage condenser has been split into two parts 3' and 133, and an inductance element 131 has been interconnected and placed between the two condensers 3' and 133. For low signal frequencies, the coil or inductance 131 can be neglected and the storage circuit acts as in Fig. 10, but for high frequencies, series resonance occurs between inductance 131 and capacitor 133 which results in a peaking effect for high audio frequencies. This, then, produces the improved response shown by curve *b* of Fig. 12. The inductance element 131 thus serves as a peaking element, and the time constant of the circuit, comprising the capacity 133 and the inductance 131, which for low audio frequencies is the same as that represented by the capacity 3 and resistor 4 in Fig. 10, appears to be reduced for high audio frequencies by way of insertion of the series peaking inductance 131 and the response curve of the system broadens out, as indicated by curve *b* of Fig. 12, during a greater portion of the frequency band, although the response drops off more rapidly as extremely high audio frequencies of the range are approached. Similar time constants and series peaking inductances are provided in the remaining stages of the system for like purposes, and hence require no further explanation. Here again, the number of tubes or stages may be increased without departing from the spirit and scope of what has been illustrated.

Reference may now be made to the circuit shown by all the Figs. 13 through 18 for further

adaptations and uses of the principles disclosed heretofore.

In the arrangements of Figs. 13 to 18, application of the storage principle will be disclosed in a field broadly termed protective or locating systems. The common features of all of these circuits is that an alternating magnetic or electrostatic field is set up in space which oscillates at the same frequency as the storage amplifier connected to the field electrodes. The system is so balanced that as long as the field is undisturbed the output indicator of the storage system is at equilibrium. As soon as any variation of the field distribution in space occurs, for instance by the intrusion of a conductive, dielectric, or ferromagnetic body or object, the particular property of the storage principle makes it possible to indicate that change in the field, not only in magnitude but also in a directional manner. Thus, not only the presence and distance of an object, but even the location thereof, is discernible.

In the arrangement particularly shown by Fig. 13, there has been disclosed what may be termed an omni-directional indicating or protective system, whereby the presence of any object, whether it be conductive or dielectric, which would tend to disturb the field equilibrium may be observed and indicated equally well in all directions of a plane. In this arrangement, the supply frequency 30 energy, which may be of any suitable value, is developed by a source of A. C. energy 150. This source of energy 150 serves in connection with the arrangement of Fig. 13 not only to supply the activating energy for energizing the plates of the several tubes of the storage amplifier system 300, as was explained in the arrangement of the figures heretofore discussed, but it also serves, as will be more particularly pointed out later, as the activating energy source to produce an electrostatic field 301 in space. The produced electrostatic field may be modified through the presence of any object 170 within the field tending to disturb a normally balanced condition. When such motion occurs, a change in the energy transfer from the source of supply frequency 150 to the input to control the amplifier will be indicated, as will be explained in what follows.

In the arrangement disclosed, the supply frequency energy from the source 150 is now fed by way of the conducting leads 152 and transformer 151 to energize the plates or anodes of the several tubes of the storage amplifier 300 by way of the conductors 12 and 25, in a manner heretofore explained. At the same time, energy from the source 150 is fed by way of an additional pair of conductors 153 to a primary winding 154 of a high voltage transformer 155 from the secondary 156 of which a substantial amount of energy at high voltages is derived and caused to produce a strong electrostatic field (for instance represented by

$\bar{E}_s$)

between a suitable field electrode element 157, such as an antenna or the equivalent, and ground 158. The voltage between the antenna element 157 and ground may be represented, for convenience, as E_s , and the capacity between the antenna and ground may be indicated conventionally by the capacity element shown in dotted outline as the capacity 159.

In order to provide the voltage E_s on the element 157, the high voltage step-up transformer 155 has been provided with a split secondary winding at which the midpoint 160 connects by

way of the conductor 161 to the grid or control electrode 23 of the first amplifier tube 1 of the system. The upper half of the split secondary 156 connects at its outer end by way of conductor 152 to the antenna element 157, while the lower end of the split secondary connects through the parallel condenser combination comprising the condensers 163 and 164 to ground at 158. Under such circumstances, the arrangement disclosed provides a bridge structure with the center tapping point 160 at an A. C. potential relative to ground which can be adjusted, and even made zero, by the condensers 163 and 164. If the bridge condensers 163, 164 are equal to the antenna capacity 159, the center tap 160 is at ground potential. If, however, the bridge condensers are set to be larger or smaller than the antenna capacity, the center tap voltage is either opposite or cophasal to the amplifier supply voltage and increases with the unbalance. Consequently, an adjustment of 163 can be found where the output meter 65 reads exactly center scale, so that a conductive grounded body 170 increases the output reading on indicator 65 while a dielectric body causes a decrease in the meter reading.

Referring back to Fig. 4b, the curve E' showed an out-of-phase relationship relative to the supply voltage Es. The adjustment herein made is of substantially the same general character. To achieve the balanced state represented by a center scale reading of indicator 65, the condenser combination 163 and 164 is preferably adjusted substantially so as to balance the capacity 159 as representing the capacity between the antenna or other element 157 and ground. This adjustment is very critical and is provided by a coarse control, in the form of a large condenser 163, and a fine control in the form of a small condenser 164. Such an adjustment is preferably facilitated by pre-setting once for all the larger of the condensers 163 and 164 and then leaving that condenser substantially fixed, after which time the smaller condenser 164 may be varied slightly to obtain balance. Generally speaking, the voltage developed across the complete secondary winding 155 is equal to twice the voltage applied to the antenna element 157 relative to ground. In order to protect against possible touching of the antenna element 157 or its lead-in 162, a suitable resistance element 166 may be provided. Likewise, in order to protect the storage amplifier system 300 against overload, a protective resistance 167 is included in the lead between the center point 160 and the control electrode 23.

If now the conditions hereinabove explained are such that in the absence of any change in the capacity between the antenna element 157 and ground 158, a substantially balanced state is continuously obtained, then a center scale reading is registered on the final output indicating device 65. However, if now there comes within the field produced between the antenna element 157 and ground 158 some object, such as that conventionally represented at 170, which would tend to disturb the field, the condition of balance heretofore achieved by way of adjustment obtained by way of condensers 163 and 164 is disturbed. The result is that the potential at the point 160 relative to ground 158 will change and an indication, as above indicated, will be produced on the output meter 65. The voltage disturbance at the bridge point 160, which would result from any body, such as that indicated at 170, coming within the field of the antenna or

other element 157, might be expressed by the following formula:

$$e_x = \frac{E_s C_s h^2 a^3}{r^6}$$

where

e_x represents the voltage between the bridge balance point 160 and ground 158;

E_s represents the voltage between the antenna and ground;

C_s represents the capacity of the antenna 157 to ground 158;

h represents the height of the antenna 157 relative to ground 158;

a is the radius of the sphere or body 170 which is tending to cause the unbalanced condition; and,

r is the distance of the body 170 from the antenna 157.

Under such conditions, it will be seen that the reaching effects, and thus the efficiency of the system, fall off as the sixth power of the distance of the object tending to disturb the balanced field.

Under such circumstances, it can be seen readily that the range of action or effectiveness of the system disclosed may be reasonably large. With a relatively high voltage of 10,000 volts existing between antenna 157 and ground 158, with the antenna roughly 75 feet high and its capacity to ground being of the order of 500 micromicrofarads, and the radius of the disturbing body approximately three feet and the sensitivity of the amplifier represented being of the order of 0.1 mv., it will be evident that from these assumed values the radius of effectiveness of the system to distinguish or determine disturbing factors coming within the field of the antenna is of the order of 150 feet. This radius may be increased, for instance, by increasing any of the factors hereinabove noted or by increasing the sensitivity of the amplifier.

Under some circumstances it is desirable to shield certain portions of the system from influence of disturbing motions and the like. For this particular purpose, the schematic illustrations of Fig. 13 indicate still another shield electrode 171 as interposed between the antenna 157 and ground 158. The shield electrode connects to ground by way of the connector 172, which connecting element may, for instance, be the outer shield of a coaxial cable of which the inner element 162 feeds energy to antenna 157. Under the circumstances, any object between the grounded auxiliary shield electrode and ground will have no effect upon the system due to the shielding effect of the element 171.

The modification disclosed by Fig. 14 is, in many respects, closely related to that hereinabove described in connection with Fig. 13, except that the system is fully insulated from ground.

Referring now particularly to Fig. 14, it may be assumed that the complete assembly included within the housing element 180 is carried particularly upon an airplane, so that a measurement of the elevation of the aircraft relative to ground 158 may easily be determined. Still further, the housing 180, for all practical purposes, may be regarded as the metallic body of the aircraft itself where there is provided an antenna 181, or other suitable form of electrode element, such as a screen or a metal coating, electrically insulated from the ship housing proper or, in the case of wood airplane construction, it is formed 70 as a metal coating on the outer surface thereof.

21

This element, however, for convenience of description, herein may be referred to as an antenna, although it should be understood that its function is primarily that of serving as one plate of the condenser element between which the capacity change, due to elevation above ground, may be measured.

Considering the arrangement still further for the purpose of description, various capacity elements have been shown by a "dash" outline with the capacity c_1 representing, for instance, the capacity between antenna 181 and ground 158, the capacity c_2 indicating the capacity between the shielding or housing 180 and ground 158, and the capacity c_3 indicating the capacity between the housing 180 and the antenna 181. It will be appreciated, of course, that it is desirable that the metallic housing element 180 encloses the complete assembly in that, when the arrangement is applied to aircraft for instance, it is essential that the pilot and other crew members be capable of freedom of motion without disturbing or unbalancing any capacity conditions caused to exist for the purpose of determining the altitude. For the same reason, the complete apparatus is housed within an electrostatic shielding element 182 which is divided into two sections 183 and 184 by means of dividing panel 185 in order to segregate the high voltage generator section from the amplifier receiver section. It is obvious that these two sections might be completely separate devices where desired.

Considering the arrangement still further, within the housing section 184 two amplifying stages, namely, stages comprising tubes 1 and 42 have, for instance, been shown, with a "dash" line intermediate tubes 1 and 42 indicating the omission of certain predetermined numbers of storage tubes between the first tube 1 and last tube 42 shown. The generator element 150 is an alternator or tube oscillator of about 20 kc. frequency, supplying energy for the storage amplifier through conductors 152 and transformer 151. At the same time, energy from the A. C. source 150 is also supplied by way of the conductor pairs 153 to the primary winding 154 of a high voltage transformer 155, of which the secondary winding 156 is divided, as explained in connection with Fig. 13. One end of the center tapped secondary winding 156 connects by way of the conductor element 186 to the antenna element 181. The other end of the secondary 156 connects to the shielding element 182 or the airplane body through the bridge condenser 187 which is of adjustable nature and serves to neutralize the capacity c_3 between the installation and the aircraft body and thus balance the bridge.

It was above pointed out that one end of the secondary winding 156 connects to antenna 181. This connection, it will be seen, is through the conductor 186 and the switching arm 189, in its closed position against contact 188, connects directly to antenna 181. In the opposite position, the switch 189 makes contact with a condenser 190 connected to the shield 182. The condenser 190 represents the effective capacity of the antenna element 181 to the airplane with the airplane resting on ground. It is for the purpose of checking the calibration of the altimeter and to protect against crash landings due to false readings. With this standard capacity connected instead of the antenna 181, the indicator device 65 or altimeter is supposed to read zero altitude under all circumstances. If this is not the case, it can be fulfilled by a readjustment of

22

the bridge condenser 187. After this adjustment, the entire calibration is checked and corrected. The accuracy of the standard condenser can be checked after each landing. If the adjustment is correct, the indicator 65 reads zero in both positions of the switch, with the plane on ground.

The storage amplifier of Fig. 14 operates in the manner described above. In the operation, the switch 189 is connected to the antenna 181 and checks on operation and calibration may be made while in flight by occasionally switching over to the connection to the condenser 190.

A further modification is shown by Fig. 15. In this form, two antennas are provided. One antenna 195 is the field producing antenna and the other antenna 196 is the receiving or pickup antenna. These antenna elements are located at predetermined spaced relationship relative to each other. Each antenna may be in the nature of metallic mesh-like screens, strands of wire, plate elements of reasonable size, or any other suitable conductive electrodes. In order to provide a suitable electrostatic field between the antenna elements 195 and 196, as well as between each of these elements and ground 158, which field might be disturbed by the presence of objects conventionally represented at 197 included therein, there is provided a source of A. C. energy 150 which feeds a portion of its output through a transformer 198, for instance, to supply high voltage of predetermined frequency to the generator antenna element 195. At the same time, the energy from the source A. C. generator 150 is fed by way of the conductor pair 152 to the storage amplifier unit 199 so as to energize and supply operating voltages thereto. The storage amplifier unit 199 is connected, as shown, to derive its control energy from the pickup antenna 196.

If now, particular reference is made, for instance, to the circuit described in Fig. 2, the meter element conventionally shown at 65 represents that meter indicated in Fig. 15, while the knob element 201 may be provided for adjusting the amplifier contained within the casing 199 to bring about a condition of rest of the meter indicator 65 with the knob element being understood to be the means by which the adjustable contact of the potentiometer 30 is varied, as in Fig. 2, to provide desired alternating current bias voltage for the first tube of the amplifier system. This bias, as was explained in the preceding figures, is of such a value as to provide, under normal conditions, a substantially mid-point indication on the meter 65. If now, some disturbing condition comes within the field, as will be explained further, it will be observed that the meter will indicate this disturbance by swinging to the right, for instance, where the disturbance causing the change is a metallic and grounded object, while the deflection will be to the left or counter-clockwise, for instance, where the field is disturbed by a non-conducting body or a conducting ungrounded body. The sense of the indication depends upon whether the effective capacity between the two antennas 195 and 196 is increased or decreased by the presence of the object 197. If the medium or object 197 is composite, as is frequently the case, and particularly so in connection with geodetic work, it may be desirable to provide several different voltage sources 150 in widely different frequency ranges, since a different indication may result for such frequencies dependent upon and signifi-

cant of the medium or object between the transmitter and the receiver antennas 195 and 196. Thus the sources 150 may be in the audio, the radio and the ultra-high frequency ranges.

Under the conditions hereinabove explained, the application of high voltage to the generator antenna 195 produces a predetermined field between it and the pickup antenna 196, which field is represented schematically by the condenser c1. A field is also produced between each of these antenna elements and ground 158. If now, a body 197 comes between the two antenna elements 195 and 196, there will be certain fields produced, represented by capacities c3 and c4 for instance, which will tend to unbalance the amplifier system 199 and cause the meter or indicator position to shift. It was above explained that if a body 197 happens to be a metallic device, the energy delivered through capacities c3 and c4 decreases because the body is at ground 158, as represented schematically, for instance, by the connection 202 between the body and ground. The effect of capacity c4 disappears, and it will be assumed that the meter or indicator 65 swings to the left to indicate decrease in the output energy of the system. If now, however, the body 197, coming within the field between the antenna elements 195 and 196, happens to be a dielectric element or an insulator with a higher dielectric constant than air, the series combination condensers c3 and c4 tend to feed more energy into the storage amplifier system 199, and it will be assumed that the indicating device indicates this state of conditions by a motion to the right.

On the diagram of Fig. 15, the insulating body or dielectric element and its effect has been indicated conventionally by the inclusion of the condenser element 203 between the body and ground. In connection with the arrangement disclosed in Fig. 15, it will be seen that the system has many applications, included among which are those of indicating the presence of metals, ores, oil or the like beneath the surface of the earth, or, for instance, indicating the presence of land mines in war time, or, on the other hand, the system may be used to indicate the presence of intruders near buildings. In cases where it is desired to indicate the presence of intruders near buildings, it will be assumed that the pickup element 196 might be constituted by a metallic or metal surface area near the edge of the building, and the antenna element 195 might then be an element suspended from the building and energized from the source 150, as explained. In this way, if persons or other intruders came between the antenna element 195 and the building, their presence would be indicated as shown.

In connection with the use of the system for geodetic purposes so as to locate metal deposits, land mines or oil, which devices are generally classed in the field of prospecting devices or searchers, then it might be assumed that the antenna elements 195 and 196 are located beneath two vehicle elements connected together by a power cord or cable and spaced from each other by a predetermined and convenient constant distance. However, it should be pointed out particularly that, under any circumstances, the amplifier unit 199, which would be contained in one of the vehicles and housed, for instance, in the housing 199, should be energized from the same A. C. source 150 that supplies energy to the antenna element 195. In this way the device be-

comes useful for purposes hereinabove indicated. Instead of one common power supply source, for practical reasons it may be desirable to provide two separate power supply sources in each separate truck, which sources are electrically synchronized with each other either by wire or radio. The latter alternative is particularly useful if the searching device is to be applied between two airplanes or between two ships at sea. Synchronization of various types of separated power supplies is well known and is not specifically herein shown.

It is important to note, in this connection, that the multiple and synchronized transmitters be arranged at mutual distances from each other which are of the order of the wave length of the supply frequency involved. In cases where the supply frequency is of the order of 30 kc., as herein assumed for instance, the separation between the transmitters would be of the order of six miles, or ten kilometers. It is only when the transmitters are so arranged that the field distribution assumes a form other than that for a single transmitter and exhibits desirable reinforcement in certain predetermined directions and, in this connection, the phenomenon might be said to compare, in a sense, with optical diffraction-gratings. It is also, of course, apparent that more than two such synchronized field generators may be arranged in a regular pattern with mutual separation distances, as above suggested.

Referring now to Fig. 16, the system disclosed in the preceding figures, and particularly in connection with the arrangements of Figs. 14 and 15, is modified so as to provide directly an indication not only of the presence of objects coming within the field, but also the relative position or direction of the objects with regard to the installation. Under such circumstances, the amplifier unit hereinabove explained, and which may consist of any desired number of stages which are contained within the housing 199, is energized from the source 150 of A. C. energy, such as a 10 kc. source, through the conductors 152 supplying the energy through the transformer 151. At the same time, the same energy source 150 feeds power through the conductors 153 and the high voltage transformer 155 so as now to supply a strong electrostatic field between a dipole arrangement of antenna elements, conventionally indicated as 215 and 216.

In the first generalized case, the housing 199 will be assumed to be connected to ground 158 by way of a conductor element 218. With the transformer arrangement 155 shown as being energized through the primary coil 154, and energy supplied through the secondary coil 156 to the dipole electrodes 215, 216, it can be seen that the dipole elements 215 and 216 ordinarily become positive and negative with respect to ground 158 at the frequency of the source 150. The center tap 160 of the transformer 155 connects by way of the conductor 161 and the protective resistor 167 and the shielding cable 221 to the control electrode 23 of the first amplifier tube 1 of the storage amplifier 199.

Contrasted with the single ended arrangement of Fig. 13, the center tap 160 may assume, in this case (Fig. 16), where a dipole is used, unbalanced potentials which may be of either positive or negative polarity relative to ground. This makes possible an indication of whether the body 197 is closer to one dipole, such as 215, or to the other dipole 216.

With the transformer contained within the housing 223, the differential condenser element 224 is so adjusted, relative to the series connected condensers 225 and 226 connected between it and the end terminals of the transformer secondary 156, that each of the outer terminals of the transformer secondary has equal and opposite voltages at all times relative to the center tap 160 and the housing 223. With the energy fed to the transformer secondary from the source being supplied to the dipole elements 215 and 216 through protective resistors 219 and 220, it becomes apparent that the potential at the point 160, relative to ground potential at 158, now will be affected by any change in the capacity between each of the elements 215 and 216 and ground 158, which effect will, in turn, be varied by the presence or absence, as well as the relative position, of some object 197 within that field.

If, now, it be assumed that the object 197 is in such a position that the capacity c_1 , indicated between the dipole element 215 and the object 197, is equal to the capacity c_2 , indicated between the dipole element 216 and the object 197, and the object 197 moves relative to the dipole elements 215 and 216 in such a manner that these capacity elements remain equal to each other, although both may increase due to the fact that the object 197 is approaching the dipole elements, the potential at the point 160 remains at ground (a "dead angle" of the locator).

However, under circumstances where the object 197 moves closer to one of the dipole elements 215 or 216 than the other in such a manner that the capacities c_1 and c_2 become unsymmetric, then it is apparent that the center tap point 160 will assume an A. C. potential and polarity relative to ground 158 so that the indicating device 65 shows an indication right or left, depending upon whether the body 197 is to the right or left of the axis of symmetry between the dipole elements 215 and 216.

It was assumed, in the discussion of Fig. 16 above, that the housing 199 containing the amplifier was connected to ground 158 by the conductor 218. Such a connection restricts the applicability of the device to stationary installations. Fortunately, however, this connection 218 to ground is not always necessary, and it may be replaced by a capacitive grounding, as indicated at C_3 , provided the capacity C_3 is relatively large compared to either of the capacities c_1 or c_2 . If this is done, the system becomes applicable to mobile stations.

Where the mobile station is a motor car, the capacitive ground C_3 might be represented by a screen positioned beneath the car relative to ground, or it may be represented by the metallic chassis of the car itself. In connection with an airplane, the same capacity might be represented by the metallic surface of the airplane relative to ground.

The general form of arrangement for mobile stations hereinabove suggested is more particularly indicated by the system disclosed by Fig. 17. Again, the source 150 supplies A. C. power of about 20 kc. to the two dipole elements 215 and 216 which are positioned outside of a metallic housing element 222 which is itself above ground 158, as represented by the "dash line" capacity element c_3 . The dipole elements 215 and 216 are energized from the source 150 through shielded conductors 223a and 226a. The amplifier arrangement itself is likewise housed in a metallic housing element 199, so that if the metallic shield 222 is assumed to be, for instance, the

airplane itself, occupants thereof may move about freely within the housing, since the housing of the amplifier 199 itself is an electrostatic shield and connected by way of a conductor 230 to the outer metallic housing 222. The remaining purposes of the operation have been fully explained in connection with Fig. 16.

It might be pointed out, in connection with this arrangement, that the system becomes particularly adapted for glide path guidance of aircraft or blind steering. In this case, the plane is so directed, when held on course, that the pilot maintains the indications on the meter 65 stationary. For these purposes, the course maintained may be defined by a power line, or by a buried cable, with the power line or cable defining, for instance, the field disturbing element 197 of the preceding figure, and the buried cable serving to guide exactly to a predetermined destination.

The arrangements of the preceding figures, it will be understood, indicate either an omnidirectional condition, as in Fig. 13, or provide indications of objects to the right or left of the plane of symmetry, as in Figs. 16 and 17. Both of these indications may also be explained in combination, for instance, by adding to the right-left indicator, as shown by Fig. 17, an omni-directional indicator, as shown by Fig. 13, with a separate vertical antenna mounted on the vehicle. A common power supply may be provided for all of these field electrodes and associated amplifiers.

According to the modification of Fig. 18, provision has been made whereby coordinate directions may be shown, or this may be considered as a panoramic location within 360°. In this use, the arrangement includes two complete storage amplifier combinations 305 and 306 and a quadrupole field generator 251, 252, 253 and 254 which produces a rotating field in space. These amplifiers are similar and, therefore, primed members represent like parts in each.

However, in order to provide the exact coordinate location of any bodies 197 coming within the field of the device, in contrast to the single phase supply frequency delivered to the amplifier unit and to the dipole elements in the arrangements of Figs. 16 and 17, for instance, a two-phase A. C. supply source 250 feeds energy to each amplifier system 305 and 306 and also to the field electrodes 251, 252, 253 and 254 by way of the push-pull high voltage transformers 255 and 256 respectively.

In connection with the arrangement of Fig. 18, it will be apparent that the amplifier units should preferably be housed within the field electrode elements 251 through 254 inclusive, rather than externally thereto, in order to make for simplicity in balancing the field. However, it is apparent that the arrangement may be remotely located, where desired.

So that panoramic observations of the presence of bodies within the field in any quadrant may readily be observed, there is provided a cathode ray indicating tube 260 with two-dimensional deflection at 90° to each other. Such deflecting means may be the deflecting electrode members 261 and 262 and the deflecting members 263 and 264 which are 90° thereto and are each conventionally represented herein. The cathode ray tube thus replaces the indicating elements of the preceding circuits and is orientated to coincide with the respective dipole axes.

The cathode ray tube anode, conventionally represented at 266, is connected to ground 258

by way of conductor 261. In order to provide voltage for deflecting the cathode ray beam within the tube 260, output energy from the last amplifier tube, for example tube 40 (such as the fourth tube of the arrangement of Fig. 2, it being assumed, for illustrative purposes, that the last two amplifying tubes 41 and 42 of Fig. 2 can be omitted) is supplied by way of the conductor 270 to the deflecting electrode 263, and likewise, for deflecting in the other quadrant, the output from the last amplifier tube 40' is supplied to the deflecting electrode 261 by way of the conductor 271.

In connection with the arrangement of this figure, however, it will be noted that in the output circuit of the last amplifying tube 40 or 40', in this condition, and for this condition only, no storage circuit need be provided, so that output energy from the tubes 40 and 40' is fed or supplied to the deflecting electrodes 263 and 261 respectively only in the form of impulses lasting for half cycles of the control frequency supplied from the source 250. The amplitude of the control energy, or, in other words, the height of the waves supplied, is a function of the voltage across the last storage circuit and therefore a function of the unbalanced condition. This, in turn, is dependent, as is evident from what was above stated, upon the size and sense of the disturbance tending to disturb the balance of the bridge system at the inputs of the two storage amplifiers 305 and 306. The system, to operate satisfactorily, is set up to provide indications of unbalance in two coordinates.

In operation, where the deflection is provided from the output from the storage amplifier, it is important to note that even in the undisturbed and balanced condition of the input condition, both amplifier units 305 and 306 develop half-wave output pulses across the conductors 270 and 271 respectively. The amplitude of these pulses will later be varied by the disturbing body in either the increasing or decreasing sense, depending upon the location of the disturbing body 197 relative to the two pairs of dipoles 251, 252 and 253, 254 respectively.

To obtain the desired indication of the presence and location of any disturbing body 197 relative to the dipoles, it is necessary to eliminate the undesirable deflection resulting from the balanced output of the amplifiers 305, 306 across the conductors 270 and 271. This is done by providing a counter-deflection field within the cathode ray tube 260 which reduces the balanced deflection to zero. If this is done, any unbalanced conditions will be indicated on the viewing target area of the cathode ray tube, both as to amplitude and polarity, and diagrams will result in the general forms shown by Fig. 18a, which are lettered I, II, III, IV, V, which show a disturbance in the quadrant between west and north and will be explained in further detail later.

To obtain the counter-deflection for the balance condition, there is provided a pair of diodes 273 and 274 which become conductive simultaneously with the output stages 40 and 40' and deliver current half-waves of the same shape and phase. The critical amplitude of these half-waves is adjusted, once and for all, by the sliding contacts of the potentiometers 276 and 279 respectively. This counter-deflecting voltage is then applied to the counter-deflecting electrodes 264 and 262 through conductors 278 and 280

respectively and is kept at a constant value throughout the operation of the system.

To describe the above in slightly more detail, at times when tube 40 is permitted to draw current by reason of the application of a positive voltage upon the plate thereof from the A. C. source 250, the diode element 273 likewise has a positive voltage supplied to its plate element 275 from the same A. C. source 250, so that current flows through the potentiometer 276 and the diode tube 273. By reason of the variable tap 277 of the potentiometer 276 and the connection thereof through conductor 278 to the deflecting electrode 264, a voltage equal and opposite to that applied to the deflecting plate 263 by the tube 40 is always developed for a normal or a balanced condition. Consequently, for the balanced state, the indicator-spot keeps at rest in the center of the screen. However, it will be appreciated that the magnitude of the voltage applied for alternate half cycles of the A. C. source 250 to the plate 264 is always constant, due to the fact that there is no modulation or change in current flow through the diode element 273 for any fixed setting of the potentiometer. Consequently, when an unbalanced condition occurs at the input to change the output from the last tube 40 (for instance) and the magnitude of the half-wave peak voltage applied to the deflecting electrode 263 in either an increasing or a decreasing sense relative to that pre-set voltage applied to the deflecting electrode 264 by the diode 273, a deflection of the cathode ray beam will take place in a direction toward that deflecting electrode which is more positive. Similar effects take place with regard to deflection in the normal direction, that is, at quadrature, with regard to the deflection produced between the deflecting plate elements 261 and 262, so that, by virtue of the current flow through the diode 274 and its associated potentiometer 279, which may be applied to the deflecting electrode 262 through the conductor 280, balance may be set up to balance normal conditions of output from the tube 40'.

If, now, reference is made to Fig. 18a, various forms of screen or cathode ray tube target patterns are indicated as they would appear upon the luminous target of the cathode ray tube. With the quadrupole or double dipole elements 251 through 254 positioned as indicated by Fig. 18, and with the cathode ray tube plates likewise indicated by Fig. 18, then a body 197 within the field at an angle α would appear as in the designation of pattern IV of Fig. 18a. The radial distance of the deflection of the cathode ray beam from the center outwardly will increase obviously as the disturbance approaches the device, in that the capacity tends to increase, as was above noted, and the system is so installed that the voltage applied to the deflecting electrodes 261 and 263 relative to the deflecting electrodes 262 and 264 respectively becomes greater. It thus becomes evident that this arrangement is capable of indicating the distance between the disturbing body 197 and the station, without regard to the direction from which the disturbing body 197 enters the field. Moreover, the system also indicates the location of the disturbing body relative to the compass direction.

The various designations in the several patterns I, II, III, IV and V of Fig. 18a are illustrative of a disturbing body 197 moving relative to the pickup from north to west at approximately the same radial distance therefrom at all times. In the absence of any disturbing body 197 coming

within the field of the system, it is apparent that the spot indication on the cathode ray tube viewing target would remain at the center of the target. It is desirable to prevent any possibility of burning the tube screen, although this does not become particularly material where the beam is not sufficiently strong to cause the tube wall to puncture due to heat, and the prior art has disclosed many ways to suppress a cathode ray beam with a failure of deflection control or in the absence of any deflection. If the disturbing body 197 is remote, the beam would tend to remain undeflected at the center of the tube and thus would be suppressed. However, when the disturbance comes closer to the system, the amplitude of the beam deflection will increase, the beam will be re-formed since the suppression system will no longer function, and a loop will appear (as shown by Fig. 18a) which points toward the disturbance, and the magnitude will be determined by the nearness of the disturbance.

It is also possible to combine such systems of the types of Figs. 13 and 17 which show, respectively, the omni-direction and the bi-directional indicators. Such combination, it will be seen, requires two storage amplifiers (as does the system of Fig. 18) with one dipole and one antenna, but requires no polyphase alternator. Contrasted with the system of Fig. 18, the combination above set forth is limited to off-course indications, so that it would be particularly useful in connection with traffic control of all types. Other modifications follow from what is hereinbefore explained and set forth.

It has been pointed out above, in connection with the circuits of Figs. 1 and 2, that the output meter 65 of storage amplifiers can be conveniently set to center scale by applying either an A. C. bias or an equivalent D. C. bias to the first stage of the system. Experimentally, the A. C. bias is easier to produce, as has been shown in Fig. 2, with the potentiometer 30 and the series resistor 31. However, in connection with A. C. operation, it should be appreciated that in the non-conductive phase the cathode of the first stage becomes negative with respect to the signal control grid 23 and, therefore, the input circuit 24 is loaded by grid emission during that part of the cycle.

An arrangement is disclosed by Fig. 19 which avoids any reaction of the amplifier into the signal source. With this modification, the stage 1 receives a D. C. cathode bias produced across the resistor 312, which bias is maintained by a blocking condenser 313 over at least one full cycle of the A. C. supply voltage connected at terminals 20. The appropriate cathode bias is brought about by rectification from the supply voltage. To this end, there is a diode system provided by cathode 8' and anode 310 of the tube 1' which is connected to the A. C. supply line 12 by a variable resistor 311. Consequently, the condenser 313 may be charged positively during the conductive cycle to any desired amount which is adjustable by the potentiometer 311, and this bias will carry over into the non-conductive half-cycle whereby any loading of the input circuit 22, 24 is eliminated. In practice, it is convenient to use, as the first stage, tubes of the type 6Q7, which are of the diode triode group and contain both the diode section as well as the amplifier section in one envelope. The remainder of the circuit of Fig. 19 is in accordance with the preceding description and acts as a storage amplifier.

Any number of stages can be used in addition to the two stages 2 and 39, as shown.

Other modifications will follow from what is above described.

Having described the invention, what is claimed is:

1. An electron tube circuit comprising a plurality of thermionic devices each having at least an anode, a cathode and a control electrode, connections between the anode of the thermionic devices and the grids of the next succeeding thermionic device to place the several thermionic devices in series cascade, a source of alternating current for supplying operating voltages for all of said thermionic devices, means for alternately connecting the anodes and cathodes of the several thermionic devices to the source of alternating current in opposite polarity so that alternate thermionic devices of the cascade are simultaneously energized by the source in alternate polarity and the cascade is formed into two alternately conductive groups of thermionic devices, an energy storage circuit connected to each of said thermionic devices to receive an electrical charge varied in accordance with the current flowing in the associated thermionic device, means to apply bias voltages only to the first of said thermionic devices and yet to establish a predetermined current flow through the entire cascade during normally conductive periods, means to utilize the charges stored in the said storage circuits to produce a control action from one to another of the said thermionic devices and the storage circuit connected thereto in sequential steps at each half-cycle of the supplied alternating current, a load circuit to receive the energy output from the said cascade of thermionic devices, and electrostatic means to supply a control voltage to the first thermionic device of the cascade to vary the energy supplied to the load circuit.
2. An amplifier system comprising a plurality of cascaded directly connected amplifier elements, a source of alternating current, means for supplying alternating current from the source to the said amplifier tubes to provide operating voltages therethrough with alternate tubes of the cascade being connected in alternate polarity with the said alternating current source so as to form the cascade into two groups of tubes alternately conductive, energy storage circuits each comprising parallelly connected resistor and condenser elements having a time constant at least equal to a time period corresponding to one-half the cycle of the source of alternating current connected to the output of each tube of the cascade, means to initiate a current flow in the first tube of the cascade, resistive means to supply an alternating current bias upon the cathode circuit of the first tube of the cascade, whereby the applied bias is effective throughout the complete cascade, means for releasing the charge from each of the storage circuits in sequence to the next direct connected tube to provide a bias voltage thereon at each half-cycle of the supplied alternating current, and an output circuit controlled by the charge in the last stage of the cascade.
3. An electronic signal relay comprising a plurality of cascaded directly connected thermionic elements, a source of alternating current, means for supplying alternating current from the source to all of the said thermionic elements to provide operating voltages therethrough with alternate thermionic elements of the cascade being connected in alternate polarity with the said alternating current source so as to form the cascade

into two groups of thermionic elements which are conductive alternately on each half cycle of the source of alternating currents, an energy storage circuit comprising parallelly connected resistor and condenser elements having a time constant at least equal to a time period corresponding to one-half cycle of the source of alternating current connected to the output of each thermionic element tube of the cascade, electrode means, means to supply alternating currents from the said source to the said electrode means to develop an electrostatic field of predetermined magnitude thereabout, means to apply a predetermined bias voltage upon only the first thermionic element of the plurality and thereby to control the current flow in the complete cascade, means to vary the current flowing in the first stage of the cascade in accordance with external changes introduced to affect the developed electrostatic field with the said current variations being determined by the relative phase of the alternating current operating voltages instantaneously applied to the tubes of the cascade and the instantaneously effective control voltage applied to vary the current flow in the first tube of the cascade, means to transfer the effect of the charge stored in the said storage circuit as a bias voltage from one to another of the said thermionic elements so that the several thermionic elements of the cascade are energized in sequence at each half-cycle of the supplied alternating current and the initial charge relayed from the first to the last of said elements with amplification, and an output stage controlled by the charge accumulated in the last of the storage circuits.

4. An amplifier system comprising a plurality of cascaded directly connected amplifier elements, a source of alternating current, means for supplying alternating current from the source to the said amplifier tubes to provide operating voltages therefor with alternate tubes of the cascade being connected in alternate polarity with the said alternating current source so as to form the cascade into two groups of tubes alternately conductive, an energy storage circuit comprising parallelly connected resistor and condenser elements having a time constant at least equal to a time period corresponding to one-half the cycle of the source of alternating current connected to the output of each tube of the cascade, resistive means to supply an alternating current bias upon the cathode circuit of the first tube only of the cascade which is effective throughout the complete cascade, means to initiate a current flow in the first tube of the cascade to charge the associated storage circuit, means for releasing the charge from each of the storage circuits in sequence to the next direct connected tube to provide a grid bias voltage thereon at each half-cycle of the supplied alternating current, and a load circuit to receive the energy output of the last tube of the plurality.

5. An amplifier system comprising a plurality of cascaded directly connected amplifier tubes, a source of alternating current, means for supplying alternating current from the source to the said amplifier tubes to provide operating voltages therethrough with alternate tubes of the cascade being connected in alternate polarity with the said alternating current source so as to form the cascade into two groups of alternately conductive tubes, energy storage circuits each comprising parallelly connected resistor and condenser elements having a time constant at least equal to a time period corresponding to one-half the cycle

of the source of alternating current connected to the output of each tube of the cascade, a plurality of field electrode means, means to apply the alternating current voltages from the source to said electrode means to develop thereabout an electrostatic field synchronously with the application of operating voltages to the cascaded tubes, means responsive to a variance in the electrostatic fields produced to cause a phase difference voltage relative to the tube operating voltages, which phase difference voltage is adapted to be applied to control the current flow in the first tube of the cascade, means to shield the said cascade from the influence of the electrostatically responsive source, a load circuit, and means to control the current flow to the load circuit under the influence of the charge stored in the storage circuit by energizing the several tubes of the cascade in sequence at each half-cycle of the supplied alternating current.

6. An amplifier circuit comprising a plurality of thermionic tubes each including at least a cathode, a control electrode and an anode, an energy storage circuit comprising a parallelly connected condenser and resistor connected serially with each tube anode, a source of alternating current, a resistance element connected in parallel with the source of alternating current, means to connect the cathode of the first tube to a predetermined point on said resistor to apply a predetermined normal bias in said tube, a direct connection between the anode of one tube and the control electrode of the next tube of the plurality to form the tubes into a direct connected cascade so that the charge acquired by the storage circuit of one tube serves, during conductive periods of the next succeeding tube, as a bias voltage thereon, means to connect the tubes of the plurality to the alternating current source in such a way that alternate tubes of the cascade are rendered conducting and non-conducting in sequence, means to control the current flow through the first tube and thereby to control in sequence each of the tubes of the plurality at alternate half-cycles of the alternating current source, and a load circuit to respond to the output energy of the said plurality of cascaded tubes.

7. An amplifier circuit comprising a plurality of thermionic tubes each including at least a cathode, a control electrode and an anode, an energy storage circuit comprising a parallelly connected condenser and resistor connected serially with each tube anode, a source of alternating current, a resistance element connected in parallel with the source of alternating current, means to connect the cathode of the first tube to a predetermined point on said resistor to apply a predetermined normal bias in said tube, a direct connection between the anode of one tube and the control electrode of the next tube of the plurality to form the tubes into a direct connected cascade so that the charge acquired by the storage circuit of one tube serves, during conductive periods of the next succeeding tube, as a bias voltage thereon, means to connect the tubes of the plurality to the alternating current source in such a way that alternate tubes of the cascade are rendered conducting and non-conducting in sequence, an impedance element to control the current flow through the first tube and thereby to control in sequence each of the tubes of the plurality at alternate half-cycles of the alternating current source, and an output circuit connected to respond to the output energy of the said plurality of cascaded tubes.

8. An amplifier circuit comprising a plurality of thermionic tubes each including at least a cathode, a control electrode and an anode, an energy storage circuit comprising a parallelly connected condenser and resistor connected serially with each tube anode, a source of alternating current, resistive means to apply a predetermined normal bias on the first tube of the group only which is effective at the output of the said first tube to apply a bias voltage to all of the tubes, a direct connection between the anode of one tube and the control electrode of the next tube of the plurality to form the tubes into a direct connected cascade so that the charge acquired by the storage circuit of one tube serves, during conductive periods of the next succeeding tube, as a bias voltage thereon, means to connect the tubes of the plurality to the alternating current source in such a way that alternate tubes of the cascade are rendered conducting and non-conducting in sequence, electrostatic means to control the current flow through the first tube and thereby to control in sequence each of the tubes of the plurality at alternate half-cycles of the alternating current source, means to supply the alternating current energy from the source to said electrostatic means to produce normally an electrostatic field which, under conditions of the said established bias, produces one predetermined current flow in the cascade and when the field is changed, due to external influence, alters the current flow in the cascade proportionately, and an output circuit to respond to the output energy of the said plurality of cascaded tubes.

9. An amplifier circuit comprising a plurality of thermionic tubes each including at least a cathode, a control electrode and an anode, an energy storage circuit comprising a parallelly connected condenser and resistor connected serially with each tube anode to receive a charge measured by the current flow in the associated tube, a source of alternating current, resistive means to apply a predetermined normal bias on the first of said tubes, a direct connection between the anode element of one tube and the control electrode of the next tube of the plurality to form the tubes into a direct connected cascade so that the charge acquired by the storage circuit of one tube serves, during conductive periods of the next succeeding tube, as a bias voltage for the following tube, means to connect the tubes of the plurality of the alternating current source in alternate polarity so that alternate tubes of the cascade are rendered conducting and non-conductive in sequence, an impedance means to control the current flow through the first tube, means to energize said impedance means by the energy of said alternating current source so that a predetermined current flow is established in the cascade for one impedance value and changes in said impedance produce related changes in the current flow in the cascade and control in sequence each of the tubes of the plurality at alternate half-cycles of the alternating current source, and an output circuit to respond to the output energy of the said plurality of cascaded tubes.

10. The amplifier claimed in claim 9 wherein the said impedance element is a capacity device.

11. The amplifier claimed in claim 9 wherein the said impedance element comprises a plurality of electrode elements between which the said alternating current source produces an electrostatic field of predetermined intensity and reach-

ing effect which is altered under the influence of external conditions to be observed.

12. A protective system comprising a plurality of thermionic tubes arranged in series cascade with direct connections from the output of the several tubes of the cascade to the input of the next succeeding tube of the cascade, separate energy storage circuits connected to receive the output energy from each tube of the cascade so that the magnitude of accumulated charge is proportional to the current flowing in the associated tube, an antenna element positioned in predetermined location relative to a plane of predetermined and fixed potential, an alternating current source of energy of predetermined frequency connected to supply voltage to the tubes of the said cascade in such a manner that cyclically alternate tubes of the cascade are simultaneously energized by the said source and the other alternate tubes of the cascade are simultaneously de-energized at a frequency corresponding to that of the said source, a connection from the source of alternating current to the antenna member to develop a predetermined strength electrostatic field between the antenna member and the plane of normally fixed potential, means to bias the first of the said cascade connected tubes to establish normally a predetermined current flow through the cascade, a bridge circuit connecting the antenna and the plane of normally fixed potential, a connection from the input of the first tube of the plurality to an intermediate point on the said bridge whereby for conditions of equilibrium the said applied bias potential alone controls the current flow in the said cascade and for external conditions modifying the normally produced electrostatic field by unbalancing the said bridge a control voltage is applied to the said amplifier to control the current flow therein, and a signal utilization circuit connected to receive the output energy from the amplifier and indicate the state of unbalance of the said bridge.

13. A protective system comprising a plurality of directly connected thermionic tubes connected in series cascade to supply the output energy from the several tubes directly to the input of the next succeeding tubes of the cascade, energy storage means connected to receive the output energy from each tube of the cascade so that the magnitude of accumulated charge is proportional to the current flowing in the associated tube, an antenna element positioned in predetermined location relative to a plane of predetermined and fixed potential, an alternating current source of energy of predetermined frequency connected to supply voltages to the tubes of the said cascade in such manner that cyclically alternate tubes of the cascade are simultaneously energized by the said source and the other alternate tubes of the cascade are simultaneously deenergized so that the stored charges bias in sequence the operative tubes, transformer means connected to receive energy from the source of A. C. and to supply said energy from one secondary terminal thereof to the antenna member to develop a predetermined strength electrostatic field between the antenna member and the plane of normally fixed potential, means to bias the first of the said cascade connected tubes to establish normally a predetermined current flow through the cascade, capacity means of a value substantially equal to the normal antenna capacity connected to the other transformer secondary terminal to form a bridge circuit connecting the antenna and the plane of normally fixed potential, a connection

from the input of the first tube of the plurality to an intermediate point on the said bridge whereby, for conditions of equilibrium, the said applied bias potential alone controls the current flow in the said cascade and, for external conditions, tending to modify the normally produced electrostatic field to cause an unbalancing of the said bridge, a control voltage is applied to the said amplifier from the said connection point, and a signal utilizing circuit connected to receive the output energy from the amplifier.

14. The circuit claimed in claim 13 comprising, in addition, shielding means to shield the amplifier from direct influence of field modifying conditions on the antenna.

15. The circuit claimed in claim 13 comprising, in addition, a second antenna member located within the normal field of the first antenna and occupying a minor portion of the field thereof, and a connection from the second antenna to the plane of fixed potential, whereby the field developed by the first antenna is free from disturbances within the field of the second antenna.

16. An electrical system for detecting disturbing conditions and establishing indications of such conditions comprising a first and a second antenna member positioned in predetermined spaced locations relative to each other and to an area of fixed potential, a source of relatively high frequency alternating current energy for energizing the first of the antenna members to produce between the said antenna member and each said area of fixed potential and the second antenna member electrostatic fields of predetermined magnitude, an amplifier unit connected to the second of the antenna members to receive energy therefrom and to respond thereto, means for energizing said amplifier by alternating current energy of a frequency value and phase relationship coinciding with that alternating current energy producing the said electrostatic fields from the first antenna member, an indicating circuit responsive to energy flowing in the said amplifier, means for establishing a normal signal bias on the amplifier to provide a predetermined current flow through the amplifier, and means responsive to any variances in the field strengths of the developed electrostatic fields to alter the signal bias on the amplifier to modify proportionally the current flow through the amplifier so as thereby to produce indications of field strength variance in the indicating circuit.

17. An electrical system for detecting disturbing conditions and establishing indications of such conditions comprising a plurality of antenna members positioned in predetermined locations relative to each other and to an area of fixed potential, a source of alternating current energy for energizing certain of the antenna members to produce between the energized members and the said area of fixed potential electrostatic fields of predetermined magnitude, an amplifier unit connected to one of the antenna members of the plurality to receive energy therefrom and to respond thereto, means for energizing said amplifier by alternating current energy of a frequency value and phase relationship coinciding with that alternating current energy producing the said electrostatic fields, an indicating circuit responsive to energy flowing in the said amplifier, means for normally establishing a predetermined current flow through the amplifier, and means responsive to any variances in the field strengths of the developed electrostatic fields to alter the current

flow through the amplifier so as thereby to produce indications of field strength variance in the indicating circuit.

18. An electrical system for detecting disturbing conditions and establishing indications of such conditions comprising a first antenna member and a second antenna member positioned in predetermined locations relative to each other and to an area of fixed potential, a source of alternating current energy for energizing the first antenna member to produce between it and the said area of fixed potential an electrostatic field of predetermined magnitude normally extending to the area of response of the second antenna member, an amplifier unit connected to receive energy from the second antenna member and to respond thereto, means for energizing said amplifier by alternating current energy of a frequency value and phase relationship coinciding with that energy applied to the first antenna, an indicating means responsive to energy flowing in the said amplifier, means for biasing the said amplifier normally so that a predetermined normal current flow passes through the amplifier to influence the indicating means, and means responsive to a change in the field strength between the first and the second antenna members to alter the current flow through the amplifier and thereby produce indications of change in field strength upon the indicating means.

19. An electrical system for detecting disturbing conditions and establishing indications of such conditions comprising a first antenna member and a second antenna member positioned in predetermined locations relative to an area of fixed potential, an alternating current source of energy for energizing the first antenna member to produce between it and the said area of fixed potential an electrostatic field of predetermined magnitude, an amplifier unit, means for energizing said amplifier by alternating current energy of a frequency value and phase relationship coinciding with that energy applied to the said two antenna members, an indicating element responsive to energy flowing in the said amplifier, means for biasing the said amplifier normally so that a predetermined current flow passes through the amplifier, and means responsive to a change in the field strength between the first and the second antenna members to supply a voltage to said amplifier to alter the current flow through the amplifier and thereby produce indications of change in field strength relative to each of the said antenna members.

20. In combination, a field electrode element, an amplifier unit and a source of alternating current energy, means to energize each of the field electrode element and the amplifier unit by said alternating current source to generate an electrical field within predetermined reaching distance of the electrode element and to provide operating energy for the amplifier at like frequency and phase relationship, an indicating circuit responsive to energy flowing in the amplifier, means to apply a predetermined normal bias upon the amplifier to establish predetermined indications in the indicating circuit for predetermined equilibrium conditions, and an interlocking connection between the field electrode and the amplifier to modify the bias upon the amplifier unit for external conditions tending to change the normally produced electrical field thereby to provide proportional changes in the indications developed in the indicating circuit.

21. A system of the class described comprising

a field electrode element, an amplifier unit and a source of relatively high frequency alternating current energy, means to energize the field electrode element by said alternating current source to generate an electrical field within predetermined reaching distance thereof and means also to provide operating voltage for the amplifier by said alternating current energy source, an indicating circuit responsive to energy output from the amplifier, means to apply a predetermined normal bias upon the amplifier to establish predetermined output energy therefrom for predetermined equilibrium conditions within the reaching range of the electrical field developed, means to apply a modification of the bias upon the amplifier unit for external conditions causing a change in the equilibrium state of the produced electrical field so that proportional changes in the output energy from the amplifier result and are observable in the indicating circuit.

22. A system of the class described comprising a field electrode element, an amplifier unit and means to generate relatively high frequency alternating current energy, means to energize the field electrode element by the said generated alternating current energy to generate an electrical field within predetermined reaching distance thereof, and means also to provide operating voltage for the amplifier by said generated alternating current energy in synchronized frequency and phase relationship relative to the energy producing the said electrical field, an indicating circuit responsive to energy output from the amplifier, means normally to establish a predetermined output current energy flow from the amplifier in its alternating current energized state for predetermined equilibrium conditions within the reaching range of the electrical field developed, means to modify the current flow through the amplifier unit for external conditions altering the equilibrium state of the produced electrical field so that proportional changes in the output energy from the amplifier result and are observable in the indicating circuit.

23. An electrical apparatus comprising an electrode element positioned in predetermined spaced relationship relative to ground, an electron tube circuit including a plurality of thermionic tubes connected in series cascade with the output of one tube being connected to the input of the succeeding tube of the cascade, an energy storage circuit connected with each tube of the cascade and arranged to be charged in accordance with the current flowing in the associated tube, a source of alternating current, means for connecting said tubes of the cascade alternately to the source of alternating current in a polarity such that the plurality of tubes of the cascade is divided into two alternately operative groups, a transformer for supplying the energy of the alternating current source and having its secondary winding connected between the first named electrode element and ground to develop an electrical field therebetween of predetermined magnitude, capacity means connected serially with the transformer secondary winding and ground to provide a balanced bridge connection of which an intermediate point on the said transformer winding is normally at a predetermined equilibrium potential relative to ground, means for biasing the said tube cascade relative to ground to a predetermined voltage whereat a predetermined normal current flows through the cascade in sequential steps from one to another of the tubes thereof, a connection from the input circuit of the first of the tubes of the cascade to the said equilibrium point on the transformer secondary whereby disturbing conditions tending to alter the capacity between the electrode member and ground produce an unbalance of the bridge and a signal voltage is applied to the said cascade and a load circuit including a visual indicating element connected to receive the energy output of the said cascade and to produce an indication of the magnitude of the departure from equilibrium value of the voltage across the said bridge.

25. The system claimed in claim 24 comprising, in addition, a second electrode member positioned intermediate the first named electrode and ground and within the electrical field reaching area thereof, means to connect said second electrode element to ground so as thereby to nullify the field producing effect of the first electrical field substantially within the area of the second electrode, whereby disturbing effects normally tending to alter the capacity between the first named electrode and ground are eliminated within the field of the second electrode.

26. In combination, a plurality of field producing electrode elements located in substantially quadrantal positions, a two-phase source of relatively high frequency alternating current, voltage step-up transformer means for energizing said electrode members from the two-phase source of alternating current energy, connections

thereof, and a connection from the input circuit of the first of the tubes of the cascade to the said equilibrium point, whereby disturbing conditions tending to alter the capacity between the electrode member and ground produces an unbalance of the bridge and a signal voltage is applied to the said cascade and a load circuit connected to receive the energy output of the said cascade and to produce an indication of the magnitude of the departure from equilibrium value of the voltage across the said bridge.

24. An electrical apparatus comprising an electrode element positioned in predetermined spaced relationship relative to ground, an electron tube circuit including a plurality of thermionic tubes connected in series cascade with the output of one tube being connected to the input of the succeeding tube of the cascade, an energy storage circuit connected with each tube of the cascade and arranged to be charged in accordance with the current flowing in the associated tube, a source of alternating current, means for connecting said tubes of the cascade alternately to the source of alternating current in a polarity such that the plurality of tubes of the cascade is divided into two alternately operative groups, a step-up high voltage transformer for supplying the energy of the alternating current source having the secondary winding thereof connected at one end to the first named electrode element to develop an electrical field between said electrode and ground of predetermined magnitude, capacity means connected serially between the other transformer secondary terminal and ground to provide a balanced bridge connection of which an intermediate point on the said transformer secondary winding is normally at a predetermined equilibrium potential relative to ground, means for biasing the said tube cascade relative to ground to a predetermined voltage whereat a predetermined normal current flows through the cascade in sequential steps from one to another of the tubes thereof, a connection from the input circuit of the first of the tubes of the cascade to the said equilibrium point on the transformer secondary whereby disturbing conditions tending to alter the capacity between the electrode member and ground produce an unbalance of the bridge and a signal voltage is applied to the said cascade, and a load circuit including a visual indicating element connected to receive the energy output of the said cascade and to produce an indication of the magnitude of the departure from equilibrium value of the voltage across the said bridge.

between opposite electrode elements of the said quadrantal arrangement to energize said connected elements with a like phase of said alternating current energy, whereby electrostatic fields are developed within a predetermined reaching area of each electrode, a pair of amplifier units connected so that one amplifier unit derives control energy from one pair of connected electrode elements and the other amplifier derives control energy from the other pair of electrode elements, means for supplying alternating current operating voltages to the said amplifiers in like frequency and phase to that energy supplied to the quadrantal electrodes connected thereto, means for normally establishing a predetermined current flow through each of the amplifiers, means responsive to field disturbances within the range of the fields developed by said electrode elements for modifying the current flowing through the said amplifiers, and a combining indicating circuit for indicating the combined modifications of current flowing in said amplifiers.

27. The system claimed in claim 26 comprising, in addition, a cathode ray tube connected to form a part of the indicating circuit, and electron beam deflecting means connected to respond to the output indications of each of the said amplifiers.

28. The system claimed in claim 26 wherein the said indicating circuit comprises a cathode ray tube having electron beam deflecting means including two pairs of mutually perpendicular electron beam deflecting elements, means for supplying the signal output of one of said amplifiers to one electron beam deflecting element of one of the said pairs, and means for supplying the output from the other of the said amplifiers also to one electron beam deflecting element of the other of said pairs, a half-wave rectifier device associated with each amplifier unit and connected to rectify the half-wave of each phase of the supplied alternating current corresponding to the half-wave period when output energy is available from the associated amplifier, and means for supplying the said rectifier energy to the second deflecting electrode of each pair associated with the instantaneously operative amplifier.

29. The apparatus claimed in claim 26 comprising, in addition, a cathode ray tube connected to form a part of the indicating circuit and electron beam deflecting means connected to respond to the output indications of each of the said amplifiers, a rectifying device associated with each amplifier to rectify the energy of that phase of the said alternating current supplying operating voltage to the amplifier, and means for supplying the rectified energy output of each of said rectifying means to control supplementarily the deflection of the cathode ray beam of the indicating device.

30. In combination, a plurality of field producing electrode elements arranged substantially to form quadrants of a circle, a two-phase source of relatively high frequency alternating current, means for developing a relatively high voltage from the source and energizing said electrode members from the two-phase source of alternating current energy, connections between opposite electrode elements of the said quadrantal arrangement to energize said connected elements with a like phase of said alternating current

energy, whereby electrostatic fields are developed within a predetermined reaching area of each electrode, a pair of amplifier units connected so that one amplifier unit derives control energy from one pair of connected electrode elements and the other amplifier derives control energy from the other pair of electrode elements, means for supplying operating voltages to the said pair of amplifiers from the said source of alternating current energy so that each amplifier is supplied with operating voltage of a frequency and phase corresponding to that energy supplied to the associated quadrantly located electrodes, means for normally establishing a predetermined current flow through each of the amplifiers, means responsive to field disturbances within the range of the fields developed by said plurality of electrode elements for modifying the current flowing through at least one of the said amplifiers, and a combining indicating circuit for indicating the modifications of current flowing in said amplifiers so as thereby to indicate the quadrantal location of the resulting field alteration.

31. The system claimed in claim 30 comprising, in addition, a cathode ray tube connected to form a part of the indicating circuit, and electron beam deflecting means connected to respond to the output indications of each of the said amplifiers.

32. The apparatus claimed in claim 30 comprising, in addition, a cathode ray tube connected to form a part of the indicating circuit, electron beam deflecting means connected to respond to the output indications of each of the said amplifiers, a half-wave rectifying device associated with each amplifier to rectify the energy of that phase of the said alternating current supplying operating voltage to the amplifier, means for supplying the rectified energy output of each of said rectifying means to control supplementarily the deflection of the cathode ray beam of the indicating device in a plane of deflection corresponding to that of the control exercised by each associated amplifier, and resistive means for altering the effectiveness of the deflection control introduced by the said rectifier.

33. The circuit claimed in claim 1 comprising, in addition, means to supply voltages from the source of alternating current to the said electrostatic means synchronously and cophaseally with the supply of alternating current to the said cascaded tubes, and means whereby the voltage supplied from the electrostatic means to control the first thermionic device of the cascade is varied in accordance with the phase shift between the control and operating voltages.

34. The amplifier system claimed in claim 4 comprising, in addition, a plurality of electrode means, means for supplying voltages to the electrode means from the source of alternating current so that an electrostatic field is developed about each electrode means, and means to so control the initiation of current flow in the cascaded tubes that current variances are proportional to the phase displacements between the controlling voltages applied to the first tube of the cascade and the operating voltages applied to all tubes of the cascade so that in the load circuit the output shall represent effectively the magnitude and direction of disturbing effects coming within the reaching field about each of the said electrodes.
